(57) **CLAIM**

The ornamental design for a “non-pyro diversionary device” as shown and described.

DESCRIPTION

FIG. 1 is a perspective view showing overall configuration of a non-pyro diversionary device according to the present invention;

FIG. 2 is a front view of the non-pyro diversionary device according to the present invention;

FIG. 3 is a left side view of the non-pyro diversionary device according to the present invention;

FIG. 4 is a right side view of the non-pyro diversionary device according to the present invention;

FIG. 5 is a top view of the non-pyro diversionary device according to the present invention;

FIG. 6 is a bottom view of the non-pyro diversionary device according to the present invention; and,

FIG. 7 is a back side view of the non-pyro diversionary device according to the present invention.

The non-pyro diversionary device of this design is used for tactical situations.
